VACUUM CLEANER

Meyric K. Rogers, La Grange Park, and Norman A. Stein-kamp, Chicago Heights, Ill., assignors to Sunbeam Corporation, Chicago, Ill., a corporation of Illinois

Filed Dec. 15, 1965, Ser. No. 182

Term of patent 14 years

(Cl. D9—2)

FIG. 1 is a perspective view of a vacuum cleaner having our design;

FIG. 2 is a rear view thereof;

FIG. 3 is a side view thereof;

FIG. 4 is a top view thereof; and

FIG. 5 is an enlarged fragmentary sectional view thereof along the section line 5—5 of FIG. 2.

The dominant features of our design reside in those portions shown in solid lines.

We claim:

The ornamental design for a vacuum cleaner, as shown and described.
